Primary Examiner — Elizabeth J Oswecki*Assistant Examiner* — Lacey Chey Bowman(74) *Attorney, Agent, or Firm* — Haynes and Boone, LLP(57) **CLAIM**

The ornamental design for an imaging device, as shown and described.

DESCRIPTION

FIG. 1 is a front, left, and top perspective view of an imaging device showing our new design;

FIG. 2 is a rear, right, and top perspective view thereof;

FIG. 3 is a front, right, and bottom perspective view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is left side elevational view thereof; and,

FIG. 9 is a right side elevational view thereof.

The broken lines in the figures are shown for the purpose of illustrating portions of the imaging device, and/or environmental matter and form no part of the claimed design. The dot-dash broken lines define the bounds of the claimed design and form no part thereof.

1 Claim, 8 Drawing Sheets(56)
